TOWERED SUSAN SERVER

William D. Warren, New York, N. Y.

Application December 1, 1955, Serial No. 39,120

Term of patent 14 years

(Cl. D44—10)

FIG. 1

FIG. 3

Fig. 1 is a front perspective view of a towered Susan server embodying my new design;

Fig. 2 is a front elevation thereof; and

Fig. 3 is a top plan view thereof.

I claim:

The ornamental design for a towered Susan server, as shown.
